UNITED STATES PATENT OFFICE.

MARY S. BOARDMAN, OF BINGHAMTON, NEW YORK.

DIVIDED SKIRT OR OVERALLS.

1,333,958.

Specification of Letters Patent. Patented Mar. 16, 1920.

Application filed January 10, 1918. Serial No. 211,184.

To all whom it may concern:

Be it known that I, MARY S. BOARDMAN, a citizen of the United States, residing at Binghamton, in the county of Broome and 5 State of New York; have invented new and useful Improvements in Divided Skirts or Overalls, of which the following is a specification.

This invention relates to improvements in 10 women's divided skirt or overalls.

The divided skirt or bloomer as ordinarily tailored does not appeal to the esthetic taste of most women, and is otherwise unsuitable for mechanical tasks. 15 Overalls, even of that type slightly varied from men's garments of the same class, while adopted by some women also offer objections, especially to women of refined taste and modesty. Such garments are, in 20 the majority of instances, ill-fitting; have inconvenient means for supporting themselves on the wearer; chafe at the crotch; are not symmetrical in form; do not properly adjust themselves at the waist line of 25 the wearer, and display or disclose the figure of the wearer to an unpleasant degree.

It is the object of the present invention to produce a garment especially designed 30 for working women that may be considered a combination of the divided skirt, bloomer and overall; one which embodies all of the desired features in these classes of garments but which overcomes or dispenses with the 35 objectionable features associated therewith, so as to produce a woman's overall that may be worn in perfect comfort and freedom of movement, which will completely protect her person from exposure, dust and 40 dirt, and which will render the wearing thereof perfectly safe as the same will embody no loose or flying parts which might be caught in machinery, etc.

It is also an object of the invention to 45 produce a woman's garment in the nature of an overall which is adjustable at the waist line so that garments of one stock size may be perfectly fitted on women of several different sizes of waist.

50 It is a further object of the invention to produce a woman's overall which is principally supported from the waist and permitted to hang in the manner of an ordinary skirt so that the same, at this portion of the garment will adapt itself to the shape of the wearer.

It is a further, and very important object of the invention to produce a woman's overall having a flap at the rear or seat thereof, adjustable at the upper edge or 60 belt line thereof to conform itself to the waistband of the garment, and which flap may be let down without necessitating the removal of or interfering with the remainder of the garment or of the adjustment of 65 shoulder straps which may be associated with the garment, and which, when in its closed position conforms itself to the shape of the remainder of the garment and fully protects the person of the wearer from 70 exposures.

It is also my purpose to produce a garment in which the waist band affords a firm support to permit of the wearer adjusting the rear flap, shoulder straps and 75 bib, when the latter are employed, etc., without interfering with the remainder of the garment, and one in which the shoulder straps are permanently attached to the back or end portions of the waist band and may 80 be adjustably connected, through the medium of a sliding buckle or the like, to the top of the bib so that the said shoulder straps may be shortened or lengthened as required. 85

It is a further purpose of the invention to produce a woman's overall in which the curved lines of the crotch seams are so formed as to afford a roomy seat and perfect comfort to the wearer in all positions, 90 and also in which the garment is so attached that the same will hang like a skirt on the wearer and present no unsightly bulge or bunchiness at the back.

I attain the foregoing objects, and others 95 by a simple arrangement and combination of parts, a satisfactory embodiment of which is illustrated by the accompanying drawings, is being understood, however, that I am not to be limited to the details 100 of the construction herein illustrated, but that I am entitled to all such changes therefrom as fall within the scope of what is claimed.

In the drawings,

Figure 1 is a front view of my improved garment.

Fig. 2 is a rear view of the same.

Fig. 3 is a detail rear view illustrating the adjustable waist and the manner in 110 which the rear flap may be let down or secured to the garment.

In the drawings I have illustrated my garment of the loose or bloomer type, but it is to be understood that my devices may be equally well used in the construction of a garment having narrow leg portions, as do men's overalls.

The garment may be made of any suitable material, such as chambray, gingham, denim, khaki, etc., and may be made with or without a bib, with or without pockets and with or without an outside belt.

As disclosed by the drawings the garment consists of two identical halves sewed together in such a manner that around the waist and hips it resembles a skirt, but below the seat it is bifurcated or two-legged.

The leg portions of the garment are indicated by the characters H, and as disclosed may have their seams, at their inner ends provided with ankle plackets J and ankle bands I. The split bands each have one of their ends provided with a button K designed to enter a buttonhole L in the other end of the band, but, of course, any desirable means may be employed for connecting the ends of the bands.

The legs, at the upper portions thereof are suspended from a waist band N which is adjustable so that the garment will fit equally well women of different waist sizes. The waist band is sewed to the garment across the front from placket M to placket M, the said plackets being arranged at the outer seams of the garment and providing the back of the garment with a flap. The end portions of the waist band are free, extending beyond the plackets and are fastened together at the center of the back of the garment. The manner of finishing and fastening these ends constitutes the adjustable feature of the waist band. Buckles or any preferred means of fastening may be used, but in the drawings I have shown one end of the band provided with buttons K and the other end provided with buttonholes L. In practice I employ three buttons K and secure the same two inches apart, while two buttonholes are employed that are spaced three inches apart. This provides for a variation of four inches so that five sizes are thus obtained, and a medium size garment will fit waists of 26, 27, 28, 29 and 30 inches. This is also an advantage to the manufacturer as well as to the wearer, as only three sizes of garments need be made, small, medium and large.

The back flap D is adjustable to correspond with the waist band, the excess fullness thereof being taken up by means of tapes O, in the device illustrated in Fig. 3. The top of the flap is provided with a facing which, at the central portion thereof, upon the inner edge of the back flap has an opening through which the tapes are passed, 65 one of the ends of each of the tapes being

secured to the outer ends of the facing, and the inner ends of the said tapes passing through the central opening in the facing. By this means, the ends of the tapes may be drawn together and knotted, thus adjusting the flap with gathers E at the upper or belt line of the flap.

If desired the garment may be provided with a bib D' which has its lower edge stitched to the front of the garment. The bib, upon the upper and inner corners thereof may be provided with buttons C. These buttons are designed to be engaged by the catch member of slideable buckles B, the said buckles being adjustably arranged on shoulder straps A, which may be employed. The shoulder straps, when employed, are permanently attached to the back or end portions of the waist band, and the sliding buckles permit of the shortening or lengthening of the straps as needed. Of course, other means, in lieu of the buckle may be provided for connecting the shoulder straps to the bib.

The garment may be provided with an outside belt F, but this belt is simply an attractive finish and is in no sense an essential feature of the garment. The belt, when used, is sewed at the lower edge in the center, to the middle of the top of the rear flap, 95 so as not to interfere with the adjustment of the flap. After the flap is adjusted the belt ends are brought around to the front and fastened in any desired or preferred manner, the said fastening means, however, permitting the proper adjustment of the belt so that the same will conform itself to the waist band which it surrounds.

It is thought, from the foregoing description, when taken in connection with the drawings, that the cheapness, simplicity, and advantages of the garment will be apparent to those skilled in the art to which the invention appertains without further detailed description.

Having thus described the invention, what I claim is:

An outer garment including a divided skirt having a waist-band adjustable as to length and also having a back flap the upper edge of which is free from the skirt and is hemmed and the side edges of which are detachably connected to the skirt at opposite sides of the upper portion thereof; the said hem at the upper edge of the back flap containing draw-tapes the inner end portions of which are extended through a central opening in the inner wall of said hem and are adjustably connected together, and said upper hemmed edge being provided at 125 its outer side with a belt to hide the edge and the appurtenances thereof.

In testimony whereof I affix my signature.

MARY S. BOARDMAN,
